UNITED STATES PATENT OFFICE.

CHARLES W. CLOUGH, ALFRED N. CLOUGH, AND WILLIAM O. SPRING, OF LOS ANGELES,
CALIFORNIA.

COMBINATION FOLDING COT AND TABLE.

1,210,605.

Specification of Letters Patent.

Patented Jan. 2, 1917.

Application filed June 21, 1915. Serial No. 35,290.

To all whom it may concern:

Be it known that we, CHARLES W. CLOUGH, ALFRED N. CLOUGH, and WILLIAM O. SPRING, citizens of the United States, residing at 5 Los Angeles, in the county of Los Angeles and State of California, have invented a new and useful Combination Folding Cot and Table, of which the following is a specification.

10 An object of this invention is to provide a device of this character which can be used as a single cot, as a double cot and as a table of different lengths, according as the various elements are arranged relative to one another.

15 Another object is to provide a device of this character which, when folded, will be of minimum size and when extended for use will be of maximum strength.

20 Other objects and advantages may appear in the subjoined detail description in connection with the drawings filed herewith.

25 The accompanying drawings illustrate the invention.

Figure 1 is a plan view of the invention arranged as a double cot, a portion of the cover being broken away for clearness of illustration. Fig. 2 is a side elevation of Fig. 1, omitting the cover, dotted lines showing some of the parts in folding positions. Fig. 3 is an end elevation of Figs. 1 and 2, omitting the cover. Fig. 4 is an enlarged sectional elevation on line indicated by x^4-x^4 , Fig. 1, dotted lines showing some of the parts in folding positions as in Fig. 2. Fig. 5 is a plan section on line indicated by x^5-x^5 , Fig. 3. Fig. 6 is a plan section on line indicated by x^6-x^6 , Fig. 3. Fig. 7 is a sectional elevation on line indicated by x^7-x^7 , Figs. 1 and 2. Fig. 8 is a side elevation of the invention arranged as a table, the cover being omitted, full lines showing the parts arranged as a shorter or partly extended table, and dotted lines showing the parts arranged

40 as a longer or fully extended table. Dash lines indicate folding position of the legs. Fig. 9 is a sectional elevation on line indicated by x^9-x^9 , Fig. 8. Fig. 10 is an end elevation of Fig. 8, showing in solid lines the invention arranged as a single cot, and the leg extensions for the table arrangement being indicated in broken lines. Fig. 11 is an enlarged detail partly in section on line indi-

cated by $x^{11}-x^{11}$, Fig. 1. Fig. 12 is a side elevation of Fig. 11. Fig. 13 is an enlarged 55 fragmental sectional detail on line indicated by $x^{13}-x^{13}$, Fig. 9. Fig. 14 is a plan section on line indicated by $x^{14}-x^{14}$, Fig. 13. Fig. 15 is an enlarged sectional detail on line indicated by $x^{15}-x^{15}$, Fig. 10. Fig. 16 is an enlarged detail of one of the brace joints. Fig. 17 is an enlarged fragmental end elevation of Fig. 1 showing the stretching device thrown out of commission. Fig. 18 is an elevation partly in section on irregular line 60 indicated by $x^{18}-x^{18}$, Fig. 17. Fig. 19 is a plan section on line indicated by $x^{19}-x^{19}$, Figs. 3 and 10. Fig. 20 is an enlarged sectional elevation on line indicated by $x^{20}-x^{20}$, Fig. 1, omitting the cover. Fig. 21 is a 70 fragmental sectional elevation analogous to Fig. 20, but showing the parts in folding positions. Fig. 22 is a fragmental inverted plan view of Fig. 20. Fig. 23 is an inverted plan view of Fig. 24. Fig. 24 is a side view 75 of the invention folded or collapsed, the side rails being partly extended. Fig. 25 is an inverted plan view of the cover folded as in Fig. 9.

There are provided telescoping side rails 80 each comprising end sections 1, 2 and an intermediate section 3; and there are provided telescoping folding end rails each comprising end sections 4, 5 and intermediate sections 6, 7, the end sections 4, 5 being pivoted 85 at 8 to links 8' which are in turn pivoted at 8'' to the side rail sections 1 or 2, as the case may be, and the adjacent ends of the intermediate sections 6, 7 being pivoted at 9 to links 10. The pivots 9 extend through 90 longitudinal slots 11 in said link 10, so as to allow for endwise movement of the end rail sections 6, 7 relative to the link 10. The link 10 is provided at its opposite ends with latches in the form of pivoted dogs or hooks 95 12 designed to engage stops in the form of pins 13 in the sections 6, 7 when said pins are seated in notches 13' at the ends of the link and the pivots 9 are at the inner ends of the slots 11'; the dogs when thrown out 100 of commission releasing the pins 13 so as to allow the sections 6, 7 to be drawn sufficiently far to disengage the pins 13 from the notches 13' so that said pins 13 will swing past the ends of the link 10 when the 105 sections 6, 7 are folded toward one another.

as in Fig. 21. The dogs 12 are normally held in latching position by coil springs 12' clearly shown in Fig. 22.

The sections 4, 6 are adjustably locked 5 against relative movement by the device shown clearly in Fig. 5, the sections 4 each being provided with a trigger 14 which is pivoted at 15 to the section 4 and which is provided at one end with a detent 16 designed to fit in any one of a number of holes 17 in the sections 6 according as the sections 4, 6 are adjusted relative to one another to bring one of the holes into registration with the detent, there being a coil spring 18 between the opposite end of each trigger and the section 4 so as to normally hold the trigger in the latching position.

The rail sections 1 to 8 inclusive are in the form of channel irons and constitute a 20 rectangular frame and said frame is provided at each of its corners with a folding or jack knife leg formed of upper and lower sections 19, 20, the upper section being pivoted at 21 to the link 8', as clearly shown 25 in Fig. 15.

The leg sections 19, 20 are in the form of channel irons and are provided with suitable means to lock them in the extended or unfolded position and for this purpose, as 30 clearly shown in Fig. 13, the upper sections 19 are provided with pivots 22 engaging slots 23 in the upper ends of the lower sections 20, the distance between the lower ends of the slots and the upper ends of the sections 35 20 being greater than the distance from the slot to the sides 24 of the leg section 19, said sides 24 thus forming stops to hold the legs against folding when the pivots are at the lower ends of said slots, and the distance 40 between the upper ends of the slots and the upper ends of the sections 20 being less than the distance from said slot to the stops 24 so that, when the pivots are in the upper ends of the slots, the legs may be readily 45 folded as indicated in dotted lines, Fig. 13.

The upper leg sections 19 are pivoted at 25 to the lower ends of folding end braces comprising lower and upper sections 26, 27 which are pivoted together at 28, the upper sections 27 being pivoted at 29 to the end rails. The upper sections 27 are provided at their lower ends with stops 30 designed to seat in notches 31, see Fig. 16, of the lower sections 26 when the braces are in 55 extended position so as to hold said braces against collapsing in a manner well understood.

When the end braces 26, 27 are folded down alongside the folded legs 19, 20 they 80 lie between the spaced apart legs and end rails as clearly shown in Fig. 24, the spacing being due to spacing collars 31' surrounding the pivots 8 between the inner faces of the end rails and the outer ends of 85 the links 8'.

The pivots 22 of the legs at one end of the frame extend through the lower ends of folding sectional side braces 32 each composed of upper and lower sections 33, 34 pivoted together at 35 and each provided 70 with a stop and slot similar to the stop and slot 30, 31 above described and indicated on the drawings by the same reference characters. The upper brace sections 33 are each pivoted at 36 to the side rails. At the 75 other end of the frame other side braces similar to those just described are provided and are designated by the same reference characters, but said other side braces are pivoted by pivots 36' to the legs at said 80 other end.

The frame is provided transversely near its middle with a folding V-shaped brace formed of sections 37, 38 pivoted to one another at 39, the upper ends of said brace 85 sections being provided with hooks 40 designed to hook into holes 41 in the inner sides of the intermediate side rail sections 3, as clearly shown in Fig. 11.

The side rail sections 1, 2 and 3 are provided in their outer sides with holes 42 to receive studs 43 fastened at intervals along flat strips 44 which are fastened along the side margins of a cover 45 constructed of suitable material such as canvas or the like, so as to form a suitable narrower support for bed clothing or dishes and the like. Each of the flat strips 44 is approximately of the same length as the side rail sections and the cover 45 is provided with slits 46 100 between adjacent ends of said strips as clearly shown in Fig. 25 for the reason hereinafter set forth. The cover 45 is provided with side extensions 47 having flat strips 48 attached thereto, said strips being similar to the strips 44 and said extensions being provided with slits 49 between the adjacent ends of strips 48. The strips 48 are provided with studs 50 designed to engage the holes 42 to form a wider support for bed 110 clothing, not shown.

The cover extension 47 along the strips 48 is provided with snap sockets 51 designed to engage snap studs 52, fastened to the cover 45 when the studs 43 are in the holes 115 42, as clearly shown in Fig. 9, so as to hold the extensions 47 folded flat against the under surface of the cover and out of the way of any person seated at the table. The cover 45 is also provided as clearly shown in Fig. 25, with snap studs and snap sockets 53, 54 designed to hold one end portion of the cover folded flat beneath the remaining portion when the parts are arranged in the contracted or shortened position shown in 120 solid lines, Fig. 8.

In order to stretch the cover 45 and take up any slack therein, the end rails are provided with suitable stretching devices in the form of toggles constructed as follows: Re- 130

ferring more particularly to Figs. 6 and 17, the end rail sections 5 are provided with toggle links 55 pivoted at 56 to the sections 5 and pivoted at 57 to operating toggle 5 levers 58 which in turn are pivoted by hook shaped pivots 59 to the sections 7, each of the operating links 58 being provided with a stop in the form of a laterally extending lug 60 designed to engage a slot 61 in the link 55 when the toggle is in the extended position shown in Fig. 6, so that the toggle will not collapse but will hold the sections 5, 7 extended against the tension of the cover 45 especially when the cover is supporting a weight such as that of a person or persons.

The cover 45 is provided at or near the middle of its ends with hooks 62 designed to hook over the adjacent ends of the end 20 rail sections 6, 7 so as to support the cover at its ends.

In practice, assuming that the device is in the folded or collapsed position shown in Fig. 24, to set up the device with the parts 25 arranged to form a single cot, the side rails will first be spread apart as indicated by the arrows *a*, Fig. 23, and then the end rails will be straightened to bring the dogs 12 into locking arrangement with the pins 13. 30 Then the end braces will be extended to brace the frame thus produced. Then the end rails will be turned through an angle of 90 degrees around the pivots 8' to swing the legs away from the side rails into vertical position relative to the side and end rails, and the side braces will be extended to hold the legs in upright position, and then the side rails will be drawn out to their full length, thus completing the arrangement shown in solid lines in Fig. 10. Next 40 the cover 45 with the extensions 47 folded in under and fastened by the snap studs and sockets 51, 52 will be fastened in place on the frame by inserting the studs 48, into 45 the holes 42.

To arrange the device as a table, the lower sections 20 of the legs will be swung downward away from the upper sections 19 and moved endwise to shift the pivots 22 50 in the lower ends of the slots 23, thereby locking the legs in their fully extended positions so as to bring the cover 45 to a convenient height for use as a table top. If the cover 45 after fastening in place is not 55 stretched sufficiently taut, the toggle devices will be thrown out of commission, and the end rails will be extended by adjusting the detents 16 to the appropriate holes 17, and then the toggle device will be thrown into 60 commission to further extend the end rails, thereby stretching the cover, thus completing the arrangement shown in Fig. 9.

If a shorter table is desired, all that is necessary is to detach one end of the cover 65 from the frame and then shorten the frame

as in Fig. 8 by telescoping the side rails, whereupon one end of the cover 45 will be folded in under the middle portion of the cover and fastened in place by the snap studs and sockets 53, 54.

To form a double cot, assuming that the parts are in the positions shown in solid lines in Fig. 10, the end rails will be drawn out to their full lengths, and then the studs 50 will be inserted in the holes 42, thus 75 completing the arrangement shown in Figs. 1, 2, 3 and 7.

To fold or collapse the device from any of the positions above described, reversal of the movements just described will bring the 80 parts in the folded positions shown in Figs. 23 and 24.

The foregoing will enable those skilled in the art to construct and operate the device.

What we claim is:

1. In combination, telescoping side rails, legs pivotally connected to the side rails, telescoping end rails pivotally connected at their ends to the legs, and provided intermediate their ends with links, said legs being foldable between said side rails and end rails when the end rails are folded, and a cover detachably fastened to the side rails.

2. In combination, telescoping side rails, legs pivotally connected to the side rails, telescoping end rails pivotally connected at their ends to the legs and provided intermediate their ends with hinges, a cover detachably fastened to the side rails, and means to extend the end rails to stretch the 100 cover.

3. In combination, telescoping side rails, folding legs formed in two sections and pivotally connected to the side rails, telescoping end rails pivotally connected at their ends to the legs and provided intermediate their ends with links and foldable between said side rails, said legs being foldable between said side rails and end rails when the end rails are folded, folding braces pivoted 110 to the legs and pivoted to the side rails, other folding braces pivoted to the legs and end rails and foldable between said legs and end rails, and a cover detachably fastened to the side rails.

4. In combination, side rails provided with holes, telescoping end rails, a cover provided along its side margins with strips, studs mounted on the strips to engage the holes when the end rails are shortened, side 120 extensions on the cover provided with other strips, other studs mounted on said other strips to engage the holes when the end rails are extended, and means to hold the end rails against contraction.

5. In combination, telescoping side rails, links pivoted to the side rails, pivot studs extending from said links, end rails provided intermediate their ends with hinges and mounted on said studs, legs pivoted to 130

the links, braces to hold the legs against folding, and a cover detachably fastened to the rails.

6. In combination, telescoping side rails,
5 end rails each comprising end sections
hinged to the side sections and intermediate
sections in telescopic relation to the end
sections, a channeled link provided with
slots and with end notches, pins near the
10 adjacent ends of the intermediate sections
passing through said slots, other pins in the
intermediate sections designed to engage the
notches when the first pins are at the inner
ends of the slots and designed to swing past
15 the ends of the link when the first pins are
at the outer ends of the slots, and dogs piv-
oted to the link and designed to hook over
said other pins when said other pins are
seated in the notches.

7. In combination, side rails, links piv-
oted to the side rails, pivot studs extending
from said links, end rails provided interme-
diate of their ends with hinges and mounted
on said studs, legs pivoted to the links, spac-
ing collars on the studs between the end rails
and legs, and braces to hold the legs against
folding.

In testimony whereof, we have hereunto
set our hands at Los Angeles, California,
this 16th day of June 1915.
